UNITED STATES PATENT OFFICE.

JOHN BECKER, OF WARREN, IDAHO.

CIGAR AND CIGARETTE HOLDER.

Application filed October 7, 1927. Serial No. 224,646.

The object of the invention is to provide a cigar or cigarette holder equipped with adjustable means for effecting a firm grip on the cigar or cigarette; to provide adjusting means for the movement of the gripping means longitudinally of the mouthpiece, so that when the cigar or cigarette is nearly consumed the gripping element may be moved back to make further smoking of the article possible until practically all of the same is consumed; and to provide a device of this character which is of simple construction and therefore susceptible of cheap manufacture and low marketing cost.

With this object in view, the invention consists in a construction and combination of parts of which a preferred embodiment is illustrated in the accompanying drawings, wherein:

Figure 1 is a side elevational view of the invention.

Figure 2 is a longitudinal sectional view.

Figures 3 and 4 are transverse sectional views taken respectively on the planes indicated by the lines 3-3 and 4-4 of Figure 1.

The gripper or chuck 10 by which the cigar or cigarette is secured in place is of tubular form and split axially on diametrically opposite sides to provide the jaws 10^a and 10^b which may move relatively towards each other to grip the cigar or cigarette by means of a U-shaped latch member 11 extending around the jaw 10^a and having pivotal mountings 13 on the jaw 10^b at diametrically opposite sides of the latter. The latch member is preferably formed of a strand of spring wire with loops 14 adjacent the pivot to provide some spring action and with a centrally disposed finger piece 15 by which it may be rocked. On the interior faces of the two jaws are provided each with a rib 16 formed by crimping the material thereof, so that a recess is provided on the outside of the jaw 10^a for the reception of the body portion of the latch when the jaws are in their widest separated positions.

A series of crimps 17 are formed on the jaw 10^b arranged in spaced relation axially of the gripper and any one of these may be engaged by the body portion of the latch, engagement of each succeeding crimp successively drawing the jaws closer together. Thus the gripper may be effectively clamped to the extremity of a cigar or cigarette.

The gripper is mounted for movement ax-

ially of the mouthpiece 18 which on diametrically opposite sides is provided with longitudinal grooves 19 in which axial ribs 20 of the gripper slide.

Operatively connected with the gripper is a sleeve 21 crimped to provide interior threads 22 engageable with a spiral rib 23 on the gripper. The sleeve is positioned on the outer end of the mouthpiece, having an inturned flange 24 abutting a circumferential shoulder 25 on the mouthpiece, this construction precluding movement of the sleeve axially in one direction and axial movement in the other direction is prevented by radial pins 26 set in the mouthpiece at diametrically opposite sides and abutting the flange on the opposite side from that which engages the shoulder. The sleeve is thus permitted angular movement on the mouthpiece but is precluded from axial movement thereon, while the gripper is precluded from angular movement but permitted axial movement. Thus the rotation of the sleeve will effect movement of the gripper to extend it from the mouthpiece, when the jaws may be readily engaged with a cigar or cigarette and the latch member set in one of the crimps to effect the best gripping operation. The sleeve may then be rotated to draw the gripper backward until the end of the cigar or cigarette seats in the end of the mouthpiece, when smoking may be proceeded with until the cigar or cigarette is almost consumed, when the gripper may be further withdrawn by the rotation of the sleeve, thus exposing the portion of the cigar or cigarette previously engaged by the gripper, when further smoking may take place until the cigar or cigarette is entirely consumed.

The invention having been described, what is claimed as new and useful is:

1. A device for the purpose indicated comprising a mouthpiece, a gripper having article-engaging jaws, said gripper being mounted for movement axially of the mouthpiece but precluded from angular movement thereon, and an adjusting sleeve engaged with the gripper and carried by the mouthpiece on which it is permitted angular or turning movement but precluded from axial movement.

2. The structure of claim 1 in which the gripper is provided with axial ribs engaging axial grooves in the mouthpiece and the

sleeve at one end provided with an inturned flange and abutting a shoulder on the mouthpiece, and pins carried by the mouthpiece and abutting the flange on the opposite side of said shoulder.

3. A device for the purpose indicated comprising a mouthpiece and a gripper bodily adjustable longitudinally thereof, the gripper comprising spring jaws, and a latch member pivotally engaged with one of the jaws and embracing the other.

4. A device for the purpose indicated comprising a mouthpiece and a gripper bodily adjustable longitudinally thereof, the gripper comprising spring jaws, and a latch member pivotally engaged with one of the jaws and embracing the other.

15 5. A device for the purpose indicated comprising a mouthpiece and a gripper bodily adjustable longitudinally thereof, the gripper comprising spring jaws, and a latch member pivotally engaged with one of the jaws and embracing the other, the latch

member being provided with a radial extension for finger actuation.

5. A device for the purpose indicated comprising a mouthpiece and a gripper bodily adjustable longitudinally thereof, the gripper comprising spring jaws, and a latch member pivotally engaged with one of the jaws and embracing the other, the latch member being provided with a radial extension for finger actuation and the jaw embraced by the latch member having a plurality of notches spaced axially of the gripper and selectively engageable by the latch member.

In testimony whereof he affixes his signature.

JOHN BECKER.
